UNITED STATES PATENT OFFICE

120,407

DESIGN FOR A DRESS

Sheldon B. Levey, Eggertsville, N. Y., assignor to Barmen Brothers Company, Inc., Buffalo, N. Y., a corporation of New York

Application February 10, 1940, Serial No. 90,191

Term of patent 3½ years

To all whom it may concern:

Be it known that I, Sheldon B. Levey, a citizen of the United States, residing at Eggertsville, in the county of Erie, and State of New York, have invented a new, original, and ornamental Design for a Dress, of which the following is a specification, reference being had to the accompanying drawing, forming part thereof.

In the accompanying drawing:

Fig. 1 is a front elevational view of a dress embodying my design.

Fig. 2 is a rear elevational view of the same.

I claim:

The ornamental design for a dress, substantially as shown.

SHELDON B. LEVEY.
